UNITED STATES PATENT OFFICE.

RALPH L. INGEBRIGTSEN, OF ABERDEEN, WASHINGTON.

GLARESHIELD FOR AUTOMOBILES.

Application filed April 3, 1924. Serial No. 703,950.

To all whom it may concern:

Be it known that I, RALPH L. INGEBRIGTSEN, a citizen of the United States, residing at Aberdeen, in the county of Grays Harbor, State of Washington, have invented certain new and useful Improvements in Glare-shields for Automobiles; and I do hereby declare the following to be a full, clear, and exact description of the invention, such as will enable others skilled in the art to which it appertains to make and use the same.

This invention relates to new and useful improvements in automobile attachments and particularly to devices for attachments to windshields.

The principal object of the invention is to provide a simple and easily operated device which may be moved into position between the eyes of the driver and the glare from the headlights of an approaching automobile.

Another object is to provide a device of this character which may be easily and quickly operated into operative position, without the employment of the hands of the driver, and which will automatically return to inoperative position, when released.

Other objects and advantages will be apparent from the following description when taken in connection with the accompanying drawing.

In the drawing:

Figure 1 is a vertical sectional view through the windshield, and a portion of the automobile, showing the invention in position thereon, and raised.

Figure 2 is an elevation as viewed from the driver's seat, the shield being in lowered position.

Figure 3 is an enlarged vertical sectional view through the knee operated device, on the line 3—3 of Figure 1.

Referring particularly to the accompanying drawing, 10 represents a portion of a windshield, having the frame 11, while 12 represents the door of the automobile. Secured to the inner face of the door 12 is an L-shaped base plate 13, the same being in an inverted position, as clearly seen in Figure 1. At the junction of the arms of the base plate 13, and extending from the opposite edge portions thereof, are the extensions 14 and 15, each of which has a socket 16 therein. The arms of the base plate are designated respectively 17 and 18, the former being the vertical one and the latter the horizontal

one. Pivotedly connected to the extension 16, which lies opposite the inner end of the arm 18, is the inner end of a lever or arm 19, the same extending longitudinally of the arm 18, and being covered, or enclosed by the wing 20, folded down from the upper edge of the arm 18. Pivotedly connected at its upper end to the arm 19, adjacent the upper end of the arm 17, is a depending link 21, the lower end of which is turned upwardly, as at 22, and confined within this turned end is the lower end of a bowed leaf spring 23. The upper end of the spring 23 is confined within the socket 16 at the upper end of the arm 17, above the arm 18. The spring is normally bowed outwardly away from the base plate, as seen in the section, Figure 3. To the outer end of the pivoted arm 19 is connected one end of a cord 24, to which reference will be made later herein.

A clamp 25, consisting of two angle plates 26, is secured in embracing relation to the upper horizontal portion of the frame of the windshield, by means of the bolts 27, passed through the frame engaging wings of the angle plates. Formed on one end of the rear wing of the clamp 25 is a rearwardly extending apertured ear 28, through which is disposed one end portion of the shaft 29. A similar pair of plates 30, constituting a second clamp 31, are disposed in embracing relation to the frame 11, at a suitable distance from the clamp 25, said clamp 31 having a rearwardly extending apertured ear 32 on one end which rotatably receives the other end portion of the shaft 29. Formed in the shaft 29, intermediate the clamps 29 and 31, is a crank 33, and encircling the shaft, with its ends engaged with the crank and the first ear 28, is a coil spring 34. On the first-named end of the shaft 29 is a radially extending arm 35, while a second, but shorter arm 36, extends radially from the other end of the shaft. A substantially angular U-shaped frame 37 has a sheet of tinted translucent material, such as celluloid, glass, or the like, secured within the channel of said frame. A clamp 38 is disposed in embracing relation to the bight portion of the frame 37, and slightly overlies the adjacent portion of the translucent material 37'. The portion of the clamp 38 outwardly of the frame 37, is formed with a pair of alined eyes 39, and disposed through these eyes is the outer end of the before-mentioned arm 35, an eye bolt

2

40 being disposed through the clamp, between the eyes and through the material 37, with a nut 41 on its other end. The arm 35 is disposed through this eye bolt and is drawn into firm frictional engagement with the clamp 38, by the nut 41. Thus the frame 37 may be adjusted longitudinally on the arm 35, to properly position the shield, when in lowered position. The other end of the 5 cord 24 is secured to the outer end of the arm 36. The action of the coil spring 34 maintains the frame 37, and the shield plate in elevated position, and when the driver desires to lower the shield to protect his 10 eyes from the glare of approaching headlights, he presses his left knee against the bowed spring 23, which causes the spring to straighten out, with the result that the lower end of the spring pushes down on the link 15 21 and rocks the lever 19 downwardly. This downward movement of the lever 19 pulls on the cord 24, and rocks the shaft 29, swinging down the shield into position in front of the eyes of the driver. Upon with- 20 drawing the knee from against the spring 23, said spring will resume its bowed condition, permitting the coil spring 34 to rock the shaft 29, and thus restore the shield into elevated position. Thus the driver, at all 25 30 times, has within his control, a shield to protect his eyes from glaring headlights, and one which is adapted to be operated without the necessity of the driver removing his hands from the wheel.

35 What is claimed is:

1. An eye shielding attachment for automobiles including a movably mounted and normally elevated shield carried by the windshield, a base mounted in juxtaposition 40 to the knee of the driver, a pivoted arm carried by the base, an arm carried by the shield, a cord connected to the said arms, a

depending element pivotally connected with the pivoted arm, and a bowed spring having one end anchored on the base and having its other end secured to the depending element said spring being arranged to be straightened by the knee of the driver to rock the pivoted arm and move the shield into lowered position before the eyes of the 45 50 driver.

2. An operating means for a glare shield comprising a casing, an arm pivotally mounted at one end in the casing and having its other end operatively connected with a glare shield, a depending link connected with the arm adjacent the pivot thereof, and a bowed flexible spring element secured at one end to the casing above the arm and having its other end secured to the lower end 55 60 of the said link, and adapted to be flexed to move the link and rock said arm.

3. The combination with a movably mounted glare shield, of means for moving the shield into operative position comprising a casing, an arm extending transversely of the casing and pivotally mounted at one end, a depending link pivotally connected with the arm intermediate the pivot thereof, and a bowed spring secured at its upper end 65 70 to the upper end of the casing above said link and having its lower end secured to the lower end of the link, whereby upon pressure being applied to the spring in the direction of the casing said spring will 75 straighten and swing the arm downwardly through the medium of the said link.

In testimony whereof, I affix my signature, in the presence of two witnesses.

RALPH L. INGEBRIGTSEN.
